ATTORNEY

UNITED STATES PATENT OFFICE.

JAMES C. MOORE, OF PHILADELPHIA, PENNSYLVANIA.

HAND-TRUCK.

1,084,287.

Specification of Letters Patent.

Patented Jan. 13, 1914.

Application filed May 4, 1911, Serial No. 625,024. Renewed March 26, 1913. Serial No. 757,046.

To all whom it may concern:

Be it known that I, JAMES C. MOORE, a citizen of the United States, residing at the city of Philadelphia, in the county of Philadelphia and State of Pennsylvania, have invented certain new and useful Improvements in Hand-Trucks, of which the following is a specification.

My invention relates to a hand-truck of a type as patented to me under date of August 18th, 1908, No. 896,228, in which a link-chain with a grip-hook is employed in the truck for supporting an article; and in such connection it relates to the employment of a link-chain and a holder having a perforated cap, whereof a link of said chain by engaging the cap constitutes a locking means for the chain gripping an article of the truck in such manner as to hold the gripped article while being transported by the truck.

The nature and scope of my present invention will be more fully understood from the following description taken in connection with the accompanying drawings forming part hereof, in which—

Figure 1, is a sectional elevation of a hand-truck supporting an article thereon and such view embracing the particular main features of my invention. Fig. 2, is a vertical sectional view on the line 2—2 of Fig. 1, of a link-chain and holder, showing one form of link-chain for such a holder; and Fig. 3, is a similar view of a modified form of a link-chain and holder, the latter in this instance having an integral perforated cap.

Referring to the drawings *a*, is a hand-truck having traveler wheels *a*¹, and handle-bars *a*².

b, is a link-chain provided with a grip-hook *b*¹, and a ring or disk *b*², to prevent the chain being entirely freed from the holder, as will be clearly understood from Figs. 2 and 3.

c, is a tubular holder wherein is mounted the chain, one end of which holder is preferably curved in form at *c*¹, as shown in Fig. 1. This holder is provided with a cap *c*², hav-

ing a perforation *c*³. The perforation of the cap *c*², in size is just sufficient to enable a link of the series of the chain *b*, to slip 50 snugly from the holder. The cap of the said holder *c*, in Fig. 2, is removable while the cap of Fig. 3, is made an integral part of the holder.

d, as shown, is a rectangular-shaped article mounted on the truck and the link-chain *b*, is extended to span the front end of the article, as clearly shown in Fig. 1. In Fig. 1, a link *b*³, of the chain *b*, partially extends from the cap of the holder *c*, and in conjunction with the perforated wall of the cap constitutes a means to lockingly hold the article on the truck irrespective of what angular position may be given the truck in handling the article as well as avoiding 65 slackening or slipping of the chain spanning the said article while being transported on the truck.

The link-chain *b*, used with the holder *c*, in Fig. 3, differs from that of Figs. 1 and 2, 70 in that the links instead of engaging each other as shown are strapped to each other at *b*⁵.

Having thus described the nature and object of my invention, what I claim as new 75 and desire to secure by Letters Patent is:—

In a hand-truck, a holder and a link-chain having a grip-hook, one end of the holder having a perforated cap, the link-chain being arranged to snugly pass through the perforation of the cap, and in conjunction with the perforated wall of such cap to form a locking means to hold the chain in any angular position while gripped to an article and against slipping or slackening of such chain 85 in said condition.

In witness whereof, I have hereunto set my signature in the presence of two subscribing witnesses.

JAMES C. MOORE.

Witnesses:

THOMAS M. SMITH,
ELIZABETH A. SHELDRAKE.
